UNITED STATES PATENT OFFICE

2,359,102

WOUND CORE REACTOR

Levin W. Foster, Pittsfield, Mass., assignor to General Electric Company, a corporation of New York

Application November 5, 1940, Serial No. 364,398

2 Claims. (Cl. 175—356)

My invention relates to electromagnetic induction apparatus, and particularly concerns reactors.

It is an object of my invention to provide a low loss inductive reactor which may be used in high power alternating current circuits and which may be fabricated by rapid economical manufacturing operations. Other and further objects and advantages will become apparent as the description proceeds.

In carrying out my invention in its preferred form, I provide an electrical winding structure which may consist of a preformed form-wound copper winding having a pair of straight winding legs, each of the winding legs being surrounded by a magnetic core in hollow cylindrical form composed of many turns of strip material, wound flatwise, one over the other, and each closely embracing the underlying turn. In order to make the inductance of the electrical winding substantially constant over a reasonable range of current values, air gaps are provided in each of the cores. The air gaps are formed by slitting the strip material. The cores are arranged with the air gaps inside the opening or window of the winding structure for the purpose of keeping magnetic losses at a minimum.

A better understanding of my invention will be afforded by the following detailed description considered in connection with the accompanying drawing, and those features of the invention which are believed to be novel and patentable will be pointed out in the claims appended hereto. In the drawing, Fig. 1 is a cross sectional view of an embodiment of my invention showing an electromagnetic induction device in one stage of the manufacturing operation, together with a clamping mechanism for holding the turns of strip during the air gap slitting operation. Fig. 2 is a cross sectional view showing the electromagnetic induction device of Fig. 1 in completed form and mounted within an enclosing tank for insulating fluid such as oil. Fig. 3 is a fragmentary view of one of the cores with a modified fastening means therefor. Fig. 4 is another fragmentary view showing a different modification of the arrangement of Fig. 3. Like reference characters are utilized throughout the drawing to designate like parts.

The electromagnetic induction device shown in the drawing by way of illustration consists of a winding structure 11 and a pair of magnetic cores 12 and 13. In the case of a reactor, the winding structure 11 consists of a continuous coil or winding of wire composed of suitable conducting ma-

terial such as copper, together with suitable insulation. Although particular reference is made in the specification to reactors, it will be understood that my invention is not limited thereto and does not exclude transformers which for certain applications may advantageously be constructed with air gaps in their cores. The winding structure 11 may be a form-wound winding which is fully preformed and completely insulated before the application of the magnetic cores to the winding legs.

The cores 12 and 13 are composed of wound strip magnetic material and may be of the type disclosed in United States Patent 2,160,588, Granfield. For the sake of obtaining as high space factor as possible the winding structure 11 is preferably formed with winding legs 14 and 15, which are straight for a distance corresponding to the axial length of the wound strip cores 12 and 13 which are of hollow cylindrical form and closely embrace the winding legs.

For eliminating saturation effects, and making the inductance of the winding substantially constant up to a reasonable maximum value of current flowing therein, the cores 12 and 13 are provided with air gaps 16 and 17 respectively, as shown in Fig. 2 in the finished reactor. The gaps 16 and 17 are relatively narrow having small dimensions in relation to the conductive winding legs 14 and 15. The cores 12 and 13 are arranged with the air gaps 16 and 17 inward or towards each other so that they come within the winding window 18. For the purpose of insulation and cooling, the reactor may be immersed in oil or other suitable insulating liquid 19 and to this end, an enclosing tank 20 is preferably provided. The tank 20 may be composed of cast iron or fabricated sheet steel such as the transformer and reactor tanks already in common use.

The use of a magnetic core composed of turns of strip, each closely embracing the underlying turn and composed of suitable low loss magnetic material such as 3 per cent cold rolled silicon steel as disclosed more in detail in the Granfield patent, results in high magnetic efficiency with low magnetic loss in the cores 12 and 13. By arranging the air gaps 16 and 17 within the winding window 18, magnetic fringing or spreading of the leakage flux crossing the air gaps 16 and 17 is reduced to a minimum, and such leakage flux as is produced flows through an air path within the winding window 18 instead of entering the material of which the tank 20 is composed. Since the tank 20 can not readily be composed of laminated magnetic material, and it would in any

event be prohibitive to attempt to construct it of low loss magnetic material, it is highly desirable to prevent the entry of any magnetic flux into the tank 20 from the magnetic circuit of the reactor. It would, of course, be too costly to utilize a non-magnetic tank such as one composed of copper, and furthermore, even in cases where no tank is employed, it is desirable to use a reactor core construction in which there is a minimum tendency for the leakage flux of the reactor to travel in a path outside the reactor as it is desirable to minimize any possibility of interaction between the reactor and external magnetic fields or between the reactor and apparatus which may be affected by fields from the reactor. Owing to the low core losses of my construction, it may be used to good advantage in power reactors, e.g., those rated at 10 k. v. a. and above.

The magnetic strip material may be applied to the winding legs 14 and 15 in the manner described in the aforesaid Granfield patent. Briefly, this consists of winding magnetic strip material on to mandrels so as to give the coil of strip so wound the size and shape which it is to have in the finished electromagnetic induction apparatus, heat-treating the strip material in this form to eliminate strains, give it a set in the desired shape and improve the magnetic properties, and thereafter unwinding from the original coil of strip and rewinding around the winding leg with the turns of strip in the same sequence in the core, assembled with the winding, as in the original coil of magnetic strip. The magnetic strip material is then readily collapsed to its original shape, leaving it in a strain-free condition, which results in low magnetic losses as explained in the Granfield patent.

In order to provide the air gaps in the core without introducing any objectionable strain in the portion of the strip adjacent the air gaps, the air gaps are preferably cut in the finished coils of strip by means of a milling cutter or saw, although a shaper may also be employed. For holding the coil during the operation of cutting the air gap and to prevent the turns of strip from separating during the operation, a clamp of any suitable type such as the clamp 21 may be provided, having a pair of jaws 22 shaped to fit the outer surface of the core and separated sufficiently at 23 to permit the use of the milling cutter or other tool for cutting the air gap 17. The assembled unit consisting of the winding structure 11 and the applied cores 12 and 13 is placed within the clamp 21 with the jaws 22 gripping one of the cores, e.g., the core 13. The air gap 17 is then cut. The gap is cut with parallel sides to make the gap length uniform for all the layers of strip in order that some layers of strip will not saturate before others and produce high losses. Preferably the construction of the winding structure 11 is such that danger of injuring the insulation thereof by the milling cutter is eliminated. For example, there may be a flat side 24 with a block 25 of suitable material, such as hard wood, temporarily or permanently inserted between the flat side 24 and the inside surface of the portion of the core where the air gap 17 is to be cut. After the air gap 17 has been cut, the jaws 22 and the clamp 21 are released, and the core 13 is turned around to the position shown in Fig. 2, having the air gap 17 within the winding window 18 of the winding structure 11. It will be understood that a similar procedure is followed in cutting the air gap 16 and bringing it within the winding window 18. This

procedure makes it possible to produce the construction illustrated although the cores each have only a single air gap and the air gap is too narrow to permit slipping the winding leg through the air gap in order to assemble the core with the conductive-winding structure.

Since the turns of strip of the cores 12 and 13 have a permanent set, no difficulty is experienced in retaining the shapes of the cores after the air gaps 16 and 17 have been cut and the air gaps have been brought to the position shown in Fig. 2. However, for the sake of providing rigidity of core structure under adverse conditions, the strip material is preferably fastened in place after the cores have been turned with the air gaps within the winding window. If desired, a non-magnetic block 26 may be inserted in the air gap after it is cut and a strap 27 of non-magnetic material may be secured as by welding or riveting to the core over the block 26, as shown in Fig. 3. This may be done before the jaws 22 and the clamp 21 are released. In this case, however, it will be necessary to provide sufficient clearance between the winding leg and the inside surface of the core to permit rotating the core to the position shown in Fig. 2. Instead of using the block 26 and the strap 27, one may also secure the adjacent turns of strap to each other by a suitable means such as a simple rivet on either side of the portion of the strip where the air gap is to be cut, or one may run a pair of line welds 28 and 29 across the edges of the strip on one side of the core, as shown in Fig. 4. The welds 28 and 29 may be made on either side of the section where the air gap 17 is to be cut. It will be understood, however, that in employing rivets or line welds care is to be taken that both line welds or rivets are in the same plane perpendicular to the cylinder axis of the core in order to prevent any eddy current path or short circuit in the turns of strip.

While I have shown particular forms of electro-magnetic induction apparatus embodying my invention and have illustrated a particular mechanism, there may be many changes and modifications without departing from the spirit and scope of my invention, and I aim in the appended claims to cover such changes and modifications.

What I claim as new and desire to secure by Letters Patent of the United States is:

1. A reactor comprising a conductive winding structure and a magnetic core, the winding structure having a winding leg surrounded by said core and a window or opening through which one side of the core passes, said core being composed of magnetic strip material closely wound spirally flatwise and having a single relatively narrow air gap therein within the winding window to eliminate excessive magnetic losses, said air gap being of small dimensions in relation to said winding leg, and means adjacent said gap for attaching adjacent turns of said magnetic strip material.

2. A method of assembling a magnetic core with a winding structure to form a low-loss power reactor, which comprises winding magnetic strip material through an opening in the winding structure and around the winding leg thereof to form a core, passing a cutting tool through an outer side of said core to form an air gap therein and rotating the core to bring the air gap within the window in the winding structure to eliminate spreading of magnetic flux induced in the core by current passing through the winding structure.
